O. SHIMWELL

WEFT CARRIER

Filed Sept. 2, 1924

Fig. 7.

Inventor
O. Shimwell
By Marks & Clerk
Atty's.

UNITED STATES PATENT OFFICE.

OLIVER SHIMWELL, OF GAWSWORTH, ENGLAND.

WEFT CARRIER.

Application filed September 2, 1924. Serial No. 735,432.

To all whom it may concern:

Be it known that I, OLIVER SHIMWELL, a subject of the King of Great Britain and Ireland, and resident of Gawsworth Old Hall, Gawsworth, in the county of Chester, England, have invented certain new and useful Improvements in Weft Carriers, of which the following is a specification.

This invention relates to shuttleless looms for weaving of the type in which the weft carrier draws a length of yarn through the warps and has for its object to provide simple and efficient means for ensuring that the weft shall be laid straight and correctly tensioned in position and shall not curl when released by the carrier and so produce short ends.

In accordance with my invention, each hook or the like upon the weft carrier which takes over the looped weft thread and draws one end thereof through the warps, is so disposed and arranged in combination with a slot or groove in the carrier that as the latter moves through the warps, it directs the weft thread to the underside of the carrier. The latter therefore lays or irons the weft upon the warp threads under tension but because of the natural adhesion of the weft and warps after such ironing process, the weft remains straight and tensioned when its end comes clear of the carrier at the end of the stroke of the latter.

It will be understood that the carrier has weft hooks and grooves at both ends so that it operates in both directions of its traverse.

The hook in the carrier is of the form which provides a point beneath which the weft thread is depressed and a closed ended raceway beneath such point in which the thread travels whilst it is guided by the slot in the carrier to the underside of the carrier in the manner before referred to.

Referring to the accompanying sheet of explanatory drawings:

Figure 1 is a side elevation, Figure 2 a plan, Figure 3 a side elevation partly in section, Figure 4 an inverted plan and Figure 5 a cross section (on the line A. B. Figure 3) illustrating a weft carrier constructed in accordance with this invention.

Figure 6 is a plan (with a portion removed) showing one of the two thread engaging hooks of the said carrier. Figures 5 and 6 are drawn to a larger scale than Figures 1 to 4.

Figure 7 is a perspective view of one of the said engaging hooks.

The same reference letters in the different views indicate the same or similar parts.

The wood body *a* of the weft carrier has a thread groove *b* at one side of its upper surface into which the weft thread is depressed by the depresser foot of the loom. At the other side of said upper surface there are attached (by screws as *c*¹, Figure 2) two weft engaging hooks *e* facing in opposite directions. The weft thread, when engaged by a hook is directed down a raceway *d*, formed integrally with the hook, and through a gap *e* providing a communication between the groove *b* and the lower surface of the carrier. Assuming, for example, that the weft carrier with the looped weft thread *f*, *g*, therein is travelling from left to right through the shed of warp threads, the weft thread will pass, from its position *f* in the groove *b* under the right hand hook *e*, and thence through the raceway *d* and gap *e* to the position *g* on the underside of the carrier. As the carrier travels forward, the increasing length of weft thread at *g* is pressed upon by the under surface of the carrier which exerts an ironing or pressing action thereon, causing it to adhere to the warp threads beneath it. A few of the warp threads are shown at *h* (Figure 1).

I claim:

1. A weft carrier for shuttleless looms, comprising a body part, two weft thread engaging hooks facing in opposite directions secured to the upper surface of the said body, and means whereby the thread engaged by said hooks is directed beneath the said body and pressed upon by its under surface.

2. A weft carrier for shuttleless looms, comprising a body part, two weft thread engaging hooks facing in opposite directions secured to the upper surface of the said body, and means consisting in part of raceways formed integrally with said hooks whereby the thread engaged by the hooks is directed beneath the said body and pressed upon by its under surface in its movement along said thread.

3. A weft carrier for shuttleless looms, comprising a body part having a weft thread groove extending along one side of its upper surface, two weft thread engaging hooks facing in opposite directions se-

cured upon the other side of said upper surface, gaps providing communications between said groove and the under surface of the body part, and raceways formed integrally with said hooks whereby the thread engaged by the hooks is directed from said groove through said gaps to a

position beneath the said body to be pressed upon by the under surface of the latter in its movement over said thread. 10

In testimony whereof I have signed my name to this specification.

OLIVER SHIMWELL.
